Primary Examiner — Cathron C Brooks*Assistant Examiner* — Karen E Kearney(74) *Attorney, Agent, or Firm* — Woodard, Emhardt, Moriarty, McNett & Henry LLP**(57) CLAIM**

The ornamental design for a digital sign with graphical user interface, as shown and described.

DESCRIPTION

The FIGURE is a front view of a digital sign with graphical user interface.

The broken lines showing text and portions of the digital sign are included for the purpose of illustrating unclaimed portions of the digital sign with graphical user interface and form no part of the claimed design.

1 Claim, 1 Drawing Sheet
